United States Patent Office.

HENRY BAKER, OF LANCASTER, PENNSYLVANIA, ASSIGNOR TO HIMSELF
AND CHRISTIAN G. HERR, OF SAME PLACE.

Letters Patent No. 99,048, dated January 25, 1870.

STOVE-PIPE DAMPER.

The Schedule referred to in these Letters Patent and making part of the same.

I, HENRY BAKER, of Lancaster city, in the State of Pennsylvania, have invented certain Improvements in Stove-Pipe Dampers, of which the following is a specification.

The object of my invention is to form a damper that will operate like the ordinary plain one, and which is provided with fixed side flues, opening above and beneath an annular flange. On the one side of this flange there is a raised fluted central disk; on the other side, a corresponding fluted ring or annular piece; so that when the flange or damper is horizontal, it closes the pipe, to check the waste of heat or draught, permitting, however, the gas and products of combustion to escape through the fluted channels or openings, forming flues between the central disk and ring-piece, which open and connect with the inner edge of the annular flange.

The drawings clearly show the construction and arrangement of the parts, so as to enable any one skilled in the art to make and use the same.

Figure 1 is a perspective view of the side to which the corrugated annular piece B is cast, or fastened by lugs b, and rivets, as shown.

A, the annular flange, with the turning-key E in place.

Figure 2 is a top view.

A, the flange.

C, the central raised disk, which is fluted parallel with the key, and having arched openings toward the circumference, (at each end of the channels, above the inner edge of the flange.)

Figure 3 shows the reverse side, with the key removed.

A, the flange.

a, slots for the keel d, on the stem D, of the key E,

(shown by Figure 5, with the ordinary screw-end and nut F.)

The annular arches or corrugations B may be cast separately with lugs b, and secured to the annular flange A by rivets, or cast with it, as, also, the fluted disk C, the inner channels of which are marked C'; and whether cast in one piece or in two, and united jointly with the flange, they constitute circular flues, as shown by Figure 4.

The short half flues, or annular portion B, admit the gas and smoke from the inside to pass out and upward through the channel C' more freely than when the disk is turned down, so that the gas, &c., can only find vent by entering the openings around the flange, and thus a great range of adjustment is obtained from a free, open draught, by turning the damper vertical to any angle, and, by attention, much waste of heat is prevented, and fuel saved.

I am aware that corrugated or fluted disks and plates are used, sliding or revolving on each other, besides other devices more or less complicated, expensive, or difficult to apply. This damper is simple, and applied as is the ordinary plain sheet-iron damper, and nearly as cheap, while it affords a wide range of adjustment, and will be found highly desirable.

What I claim, is—

The arrangement of the annular flange A and fluted disk C, in combination with the short flues or annular corrugations B, constructed and operated in the manner shown and described, for the purpose set forth.

HENRY BAKER.
